US00D751050S

(12) **United States Design Patent**
Song et al.

(10) **Patent No.:** US D751,050 S
(45) **Date of Patent:** ** Mar. 8, 2016

(54) **MOBILE TELEPHONE**

- (71) Applicant: **HISENSE MOBILE COMMUNICATIONS TECHNOLOGY CO., LTD.**, Shandong (CN)
- (72) Inventors: **Chunyan Song**, Shandong (CN); **Lili Guo**, Shandong (CN); **Mang Lu**, Shandong (CN)
- (73) Assignee: **HISENSE MOBILE COMMUNICATIONS TECHNOLOGY CO., LTD.**, Shandong (CN)

(**) Term: **14 Years**

(21) Appl. No.: **29/477,169**

(22) Filed: **Dec. 19, 2013**

(51) **LOC (10) Cl.** 14-03

(52) **U.S. Cl.**

USPC ..... **D14/138 G**

(58) **Field of Classification Search**

USPC ..... D14/138 G, 138 AD, 341, 346, 345, D14/138 R, 496, 203.1, 203.3, 203.5, 203.7, D14/248, 218, 250; 455/575.1, 556.2, 455/575.3, 575.4; D21/517, 329; 379/433.01, 433.04; D10/65, 78; 361/679.3, 679.56; D13/168
